UNITED STATES PATENT OFFICE.

WILLIAM R. BARKER, OF VANZANT, MISSOURI.

FENCE-POST DRIVER.

1,310,272.

Specification of Letters Patent. Patented July 15, 1919.

Application filed August 10, 1917. Serial No. 185,514.

To all whom it may concern:

Be it known that I, WILLIAM R. BARKER, a citizen of the United States, residing at Vanzant, in the county of Douglas and State of Missouri, have invented certain new and useful Improvements in Fence-Post Drivers; and I do hereby declare the following to be a full, clear, and exact description of the invention, such as will enable others skilled 10 in the art to which it appertains to make and use the same.

This invention relates to fence post drivers and more particularly to portable fence post drivers and the primary object of the 15 invention is to provide an improved machine for driving fence posts, that can be manually operated with a minimum amount of exertion.

Another object of the invention is to provide an improved portable machine for driving fence posts, in which the mechanism for driving the post can be adjusted at all times so as to occupy a position in a vertical plane, no matter at what angle the vehicle 25 supporting the mechanism is lying.

A further object of the invention is the provision of means for adjusting the driving mechanism laterally of the vehicle body so that if the vehicle is not driven to the 30 correct position over the place where the post is desired to be driven in the ground, the driving mechanism can be moved and placed over the desired position.

A still further object of the invention is 35 the provision of means for holding the post in correct position while the same is being driven into the ground.

A still further object of the invention is the provision of a ratchet mechanism for 40 raising the weight, and means for releasing the ratchet mechanism when the weight has reached a certain height.

A still further object of the invention is 45 to provide a machine for driving fence posts of the above character which is durable and efficient in operation, one that is simple and easy to manufacture, and one that can be placed upon the market at a reasonable price.

With these and other objects in view, the 50 invention consists in the novel construction, arrangement and formation of parts, as will be hereinafter more specifically described, claimed and illustrated in the accompany-

ing drawings, forming a part thereof, in 55 which—

Figure 1 is a side elevation of the improved fence post driving mechanism, showing the same mounted on a vehicle,

Fig. 2 is a top plan view of the improved 60 fence post driving mechanism showing the rear portion of the supporting vehicle,

Fig. 3 is a rear elevation of the improved driving mechanism,

Fig. 4 is a vertical section, taken through 65 the improved device,

Fig. 5 is a horizontal section taken through the improved fence post driving means showing the manner of mounting the same on a vehicle body and showing the 70 weight guiding means removed,

Fig. 6 is detail fragmentary view partly in section, showing the means for adjusting the angle of the driving mechanism in relation to the vehicle body,

Fig. 7 is a fragmentary detail sectional view through the improved ratchet mechanism, and

Fig. 8 is a detail elevation of the im- 80 proved ratchet mechanism.

Referring to the drawings in detail, wherein similar reference numerals designate corresponding parts, throughout the several views, the numeral 1 generally indicates the improved fence post driving 85 mechanism, which is adapted to be mounted upon an ordinary or any preferred type of vehicle 2.

The vehicle 2 includes a front wheel 3, the rear wheels 4, front and rear axles 5, the 90 rear bolster 6, the front lower bolster 7, the upper front bolster 8 which is swivelly connected to the lower bolster by the ordinary king bolt 9, the front hound 10, rear hound 10^a, coupling pole 10^b, the connecting tongue 95 11, and the standards 12.

The improved fence post driving mechanism 1 includes a supporting frame 13 which consists of a pair of spaced diverging bars 14 and 15 respectively, which extend longitudinally of the vehicle body and have their forward ends rigidly secured to the upper front bolster 8. The bars 14 and 15 extend slightly beyond the rear bolster 6, upon which they are slidably mounted and have 105 their rear ends rigidly connected to a relatively large substantially rectangular supporting plate 16. Suitable angle irons 17

connect the plate with the bars and firmly braces the same against all strain. A U-shaped frame 18 has its bight portion 19, swivelly connected to the supporting plate 16 by means of a bolt 20, which extends through registering apertures formed in the central portion of the bight portion 19 and the supporting plate 16. A suitable washer 21 spaces the bight portion from the plate 16. The ends of the plate 16 are rounded and one end of the same has connected thereto an arcuate plate 22, which has a plurality of apertures formed therein which are adapted to receive a pin 23 loosely carried by the angle lever 24, which is carried by the frame 18 and has an operating handle 25. The lever has an aperture, which is adapted to register with any one of the apertures formed in the arcuate plate 22, and the pin 23 is adapted to fit in the registering apertures to hold the frame 18 in the desired position in relation to the vehicle body. The U-shaped member 18 consists of the bight portion 19 and the spaced parallel legs 26 which pivotally supports the inner frame 27. The inner frame 27 includes the lower spaced parallel bars 28, which have connected thereto adjacent the ends thereof, upwardly inclined supporting standards 29 which converge toward the upper portion thereof and they have rigidly secured thereto at the upper portion thereof, the elongated substantially rectangular guide housing 30 which is open at both ends. This guide housing 30 receives a reciprocably mounted weight 31, which will be herein-after more fully described.

The spaced parallel bars 28 are pivotally secured to the legs 26 of the U-shaped frame 18 by means of bolts, 32 which extend through registering apertures formed in the central portion of the bars 28 and the legs 26. The bolts 32 have suitable nuts 33 threaded on their ends which hold the bolts in correct position. The free end of one leg 26 of the U-shaped frame 18 is rounded and receives an arcuate plate 34, which is provided with a plurality of apertures and one of the bars 28 carries an outstanding lever 35 which is bent intermediate its ends to provide the outwardly extending ear 36, which is suitably apertured and this aperture is adapted to register with any one of the apertures formed in the arcuate plate 34. A pin 37 is loosely carried by the operating lever 35 and this pin is adapted to be received in the registering apertures and holds the inner frame 27 in any desired angle in relation to the U-shaped frame 18. The operating lever 35 is provided with a handle 36' by means of which the inner frame is adjusted.

The spaced supporting bars 14 and 15 extend longitudinally of the vehicle 2 and are secured adjacent their rear ends to a pair of

spaced guide bars 37', which straddle the rear bolster 6 of the vehicle, and the bolster 6 has an inwardly extending ear 38 which pivotally receives the inner end of an operating lever 39, which is pivotally secured to the outermost guide bar 37'. The outermost guide strip 37' has an upwardly extending pin 40 secured thereto adjacent one end thereof, which extends through a slot 41 formed in the operating lever 39 intermediate the ends thereof. By moving the operating lever the supporting bars 14 and 15 can be moved laterally of the vehicle body, and thus position the post driving mechanism 1 in any desired position in relation to the vehicle body.

A plate 42 is rigidly secured to the upper surface of the guide housing 30 and to the upper surface of the converging standards 29. Suitable braces 43 extend from the forward edge of the plate to the standards 29 and serve to support this plate. A pulley housing 44, inclosing a suitable rotatably mounted pulley 45, is rigidly secured on the upper portion of the plate 42 and a suitable rope 46 is trained around the pulley and extends through an aperture 47 formed in the plate 42, into the guide housing 30 and is connected to a loop 48 carried by the weight 31. The opposite end of the rope 46 is secured as at 50 to a grooved pulley wheel 51 which is rotatably mounted on a sleeve 52. The sleeve 52 has formed on its inner end a substantially flat circular plate 53 through which the bolt 32 extends and rigidly holds the sleeve 52 in position. The sleeve 52 has an outwardly extending reduced extension 54 formed thereon, which rotatably receives the hand crank 55. The pulley wheel 51 has a collar 56 rigidly mounted therein which has a clutch face 57, which corresponds with the clutch face 58 formed on the crank 55. A spring 59 extends around the extension 54 and bears against the crank 55 and a washer 60, which is removably supported on the outer end of the extension 54 and this coil spring normally holds the clutch face of the crank in engagement with the clutch face of the collar 56 carried by the pulley 51. The sleeve 52 has an outwardly extending inclined lug 61, which is adapted to be engaged by a corresponding inclined lug 62 by the crank 55 and when the crank has been turned substantially one revolution the lugs 61 and 62 will engage each other and the lug 61 will force the clutch face 58 of the crank 55 out of engagement with the clutch face formed on the collar 56 carried by the pulley 51 and allows the weight to slide down the guide housing. Thus by turning the crank, the same will rotate the pulley until substantially one revolution has been made, when the lugs will force the crank out of engagement with the collar and allow the pulley to ride free on the sleeve 52 and thus allow the

weight to descend. This operation can be repeated as much as required to drive the post (not shown) in the ground. A stop 63 is carried by the inner surface of the pulley 51 adjacent the periphery thereof and is adapted to engage a stationary stop 64 carried by one of the legs 26 of the U-shaped frame. The stationary stop 64 limits the movement of the pulley 51 when the weight 10 31 slides down the guide housing. The lower end of the guide housing 30 is cut away, so as to provide means for entering the guide housing and the same is closed by a hinged door 65. The door is secured to the 15 housing by suitable hinges 66 and is closed by a pivoted latch 67. This construction of the guide housing forms means whereby the upper end of the post can be inserted in the guide housing and the door closed, which 20 will hold the post (not shown) in position until the weight 31 has driven the same into the ground.

By the construction described above, it can be seen that an improved fence post 25 driver has been formed, in which the post driving mechanism proper can be adjusted laterally of the vehicle and also positioned and held in a vertical plane, no matter what angle the vehicle body may be lying. 30 While the above device has been shown and described as especially adapted for driving fence posts, it is to be understood that the machine can be used to the best of advantage for driving well pipe casings, piles, 35 and other articles of a similar type.

In practice, I have found that the form of my invention, illustrated in the accompanying drawings and referred to in the above description, as the preferred embodiment, is

the most efficient and practical; yet realizing the conditions concurrent with the adoption of my device will necessarily vary, I desire to emphasize the fact that various minor changes in details of construction, proportion and arrangement of parts may 40 be resorted to, when required, without sacrificing any of the advantages of my invention 45 as set forth.

What is claimed is:—

1. In a device of the character described, 50 the combination with a supporting vehicle, of a U-shaped frame, means pivotally securing the bight portion of the frame to the vehicle, a second frame pivotally carried by the U-shaped frame, means for adjustably 55 holding the frames in relation to each other and to the vehicle body, a guide carried by the last mentioned frame, a weight reciprocally mounted in the guide, and means for operating the weight.

2. A device of the character described, the combination with a supporting vehicle including a rear bolster, of a frame slidable on the bolster, a U-shaped frame pivotally secured to the first mentioned frame, a guide 65 carried by the U-shaped frame, a weight mounted in the guide, means for operating the weight, and an operating lever pivotally secured to the bolster and operatively connected to the sliding frame, as and for the 70 purpose specified.

In testimony whereof I affix my signature in presence of two witnesses.

WILLIAM R. BARKER.
